UNITED STATES PATENT OFFICE.

JOZEPH POCZATEK, OF CHICOPEE FALLS, MASSACHUSETTS.

DESIGN FOR A PICTURE-FRAME.

53,524.

Specification for Design.

Patented July 8, 1919.

Application filed January 30, 1919. Serial No. 274,142. Term of patent 3½ years.

To all whom it may concern:

Be it known that I, JOZEPH POCZATEK, a subject of the Emperor of Austria, and a resident of Chicopee Falls, in the county of Hampden, and the State of Massachusetts, have invented a new, original, and ornamental Design for a Picture-Frame, of which the following is a specification, reference being had to the accompanying drawing, forming part thereof.

The figure is a plan view of a picture frame, showing my new design.

I claim:—

The ornamental design for a picture frame, as shown.

JOZEPH POCZATEK. [L.S.]
